(57) **CLAIM**

We claim, the ornamental design for a dispenser, as shown and described.

DESCRIPTION

FIG. 1 is a side perspective view of an embodiment of a dispenser showing our new design;

FIG. 2 is a bottom plan view of the dispenser of FIG. 1;

FIG. 3 is a side view of the dispenser of FIG. 1; and,

FIG. 4 is a top plan view of the dispenser of FIG. 1.

The broken lines in the figures show structure or boundaries that are not part of the claimed design, but rather show the environment in which the design is associated, or show portions of the article in which the design is embodied or applied to that are not considered part of the claimed design.
